(57) **CLAIM**

The ornamental design for a spherical ride element having right-sided openings, as shown and described.

DESCRIPTION

FIG. 1 is a perspective view of the spherical ride element having right-sided openings in accordance with the present invention;

FIG. 2 is a left side view of the spherical ride element having right-sided openings of FIG. 1;

FIG. 3 is a right side view of the spherical ride element having right-sided openings of FIG. 1;

FIG. 4 is a front side view of the spherical ride element having right-sided openings of FIG. 1;

FIG. 5 is a back side view of the spherical ride element having right-sided openings of FIG. 1;

FIG. 6 is a top view of the spherical ride element having right-sided openings of FIG. 1; and,

FIG. 7 is a bottom view of the spherical ride element having right-sided openings of FIG. 1.
